UNITED STATES PATENT OFFICE

2,200,499

PAD HOLDER

Evangel A. Haveles, Los Angeles, Calif.

Application January 18, 1939, Serial No. 251,563

10 Claims. (Cl. 281—1)

My invention relates to a pad holder for holding pads of the type that are perforated near one end leaving a stub when the sheets are torn at the perforation line and may be of the manifolding type. The objects of my invention are:

First, to provide a pad holder of this class which is easily connected with a table, desk, counter or the like and easily disconnected therefrom;

Second, to provide a pad holder of this class with a specially hinged flap to be positioned under some of the top leaves of the pad for manifolding or other purposes and which serves to facilitate the severing of the upper leaves from the pad;

Third, to provide a pad holder of this class with novel means for supporting the pad at the stub portion;

Fourth, to provide a pad holder of this class in which the flap is so supported that it is operable on a very fixed or thin pad adaptable to varying thicknesses of pad;

Fifth, to provide a pad holder of this class in which the flap may be shifted from its relation with the pad and may be used as a support to write upon if desired;

Sixth, to provide a pad holder of this class in which the pad may be quickly positioned or removed from the holder;

Seventh, to provide a pad holder of this class which may be used in connection with relatively wide or large pads of either the manifolding type or straight pads; and

Eighth, to provide a pad holder of this class which is very simple and economical of construction, easy to manufacture, easy to operate, efficient in its action, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application in which:

Figure 1 is a top or plan view of my pad holder shown positioned on a fragmentary portion of a table or desk showing the flap in solid lines shown positioned on top of the pad and by dotted lines in open out of the way position; Fig. 2 is a rear end view thereof showing the pad support securing member in its relation with a fragmentary portion of a table, desk or the like;

Fig. 3 is a fragmentary side elevational view thereof; and Fig. 4 is a sectional view of a fragmentary portion taken from the line 4—4 of Fig. 3.

Similar characters of reference refer to similar parts and portions throughout the several views of the drawing:

The pad support 1, pad support securing member 2, pad support securing bolt 3, flap member 4, pad clamp member 5 and pad clamp member 6 spring 6 constitute the principal parts and portions of my pad holder.

The pad support 1 is substantially rectangular in shape and is provided with a flat portion upon which the bottom of the pad rests. It is provided along one side with an upwardly extending flange portion 1a which supports the pad and prevents it from twisting or shifting thereon. On the opposite side is another flange 1b which is provided with two openings 1c and 1d. These openings 1c and 1d are adapted to provide the clearance for the hinges 4a and 4b of the flap member 4 when the flap member 4 is opened in the dotted line position as shown in Fig. 1 of the drawing. The portion removed for the openings 1c and 1d is turned backwardly at right angles and forms slotted hinge supporting members 1e and 1f which are provided with vertical slots 1g as shown best in Fig. 2 of the drawing. It will be noted, however, that these members 1e and 1f may be separate and supported by reinforcing members 1h and 1i which are secured to the members 1b at opposite sides of the openings 1c and 1d to provide reinforcing for supporting these members 1e and 1f. Shiftably mounted in the slots 1g are pin members 4c which are secured to downwardly extending portions 4d on the hinge members 4a and 4b and these hinge members 4a and 4b extend downwardly and then inwardly and are preferably integrally connected with the flap member 4 as shown in the drawing.

This flap member 4 is substantially the width of the pad and fits loosely between the flanges 1a and 1b and by reason of the particular shape of the hinge members 4a and 4b and their sliding relation with the slotted members 1e and 1f, this flap may be arranged for positioning between the leaves or on top of the upper leaves of varying thickness of pads positioned on the supports 1. This flap member is provided with an extended handle portion 4e which extends outwardly from under the pad or from the end of the pad so that it may be readily grasped for shifting the flap member to the position shown by dotted lines in Fig. 1 and if desired for severing some of the

upper leaves of the pad by grasping the leaves in connection with this flap member and raising the flap member. These flange members 1a and 1b are provided with holes near the front end in 5 which is mounted a pin 5a upon which is pivotally mounted the pad clamp member 5. This pad clamp member 5 is provided with a flat upper side portion 5b which is provided with an integral up turned handle portion 5c. The flat portion 5b 10 is adapted to engage the stub portion of the pad near the perforation line at its backward edge. It is provided with backwardly turned side portions 5d, shown best in Fig. 3 of the drawing, which is provided with holes therein through 15 which the pin 5a extends. This member is also provided with a front side portion 5e which closes the front end of the support as shown best in Fig. 3 of the drawing. Mounted around the pin 5a is a torsion spring 6, the one end 6a extending 20 up through the portion 5b at the one corner and the other end 5f supported against the end of the member 1, thus tending to hold the member 5 in tight relation with the stub of the pad, as shown best in Fig. 3 of the drawing, but may be raised 25 by grasping the handle portion 5c and pressing it forwardly for removing or positioning a pad member in position on the support.

In order to support the pad support 1 so that it may be readily connected or disconnected with 30 a table, desk or the like, there is provided a pad support securing member 2 which is provided with a backwardly extending flange 2a at its upper side which is adapted to fit over the upper side of one edge of a desk, table, counter or the like. It is provided with an offset portion 2b 35 which is provided with a slot adapted to receive a downwardly extending lip 1f from the pad support 1 at the back end thereof, shown best in Figs. 2 and 3 of the drawing. This offset portion 40 is provided with a loop member 2c which is adapted for a string for supporting a pencil to be used in connection with the pad. This member 2 extends downwardly some distance and is provided with a right angle turned portion 2d at its 45 lower end which is provided with a threaded hole 2e which is adapted to receive the bolt 3 for clamping the member 2 rigidly in position with a counter, shelf or the like. This member 2, it will be noted, is provided with reenforcing offset 50 portions 2f to strengthen the same.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I 60 claim as new and desire to secure by Letters Patent is:

1. In a pad support of the class described, a relatively flat substantially rectangularly shaped support member provided with a flange at each side thereof extending upwardly, vertically slotted hinge members extending at right angles to one of said flanges, and a flap provided with offset hinge members with pins mounted in said slots shiftable upwardly and downwardly therein.
2. In a pad support of the class described, a relatively flat substantially rectangularly shaped support member provided with a flange at each side thereof extending upwardly, vertically slotted hinge members extending at right angles to one of said flanges, a flap provided with offset

hinge members with pins mounted in said slots shiftable upwardly and downwardly therein, said flap member provided with a handle portion extending from one end at one side thereof.

3. In a pad support of the class described, a 5 relatively flat substantially rectangularly shaped support member provided with a flange at each side thereof extending upwardly, vertically slotted hinge members extending at right angles to one of said flanges, a flap provided with offset 10 hinge members with pins mounted in said slots shiftable upwardly and downwardly therein, said flap member provided with a handle portion extending from one end at one side thereof, and a spring actuated clamp member mounted at one 15 end of said support.

4. In a pad support of the class described, a relatively flat substantially rectangularly shaped support member provided with a flange at each side thereof extending upwardly, vertically slotted 20 hinge members extending at right angles to one of said flanges, a flap provided with offset hinge members with pins mounted in said slots shiftable upwardly and downwardly therein, said flap member provided with a handle portion 25 extending from one end at one side thereof, a spring actuated clamp member mounted at one end of said support, including a pin mounted in the extended ends of said flange members, a clamp member pivotally mounted on said pins, and a 30 torsion spring mounted on said pins and secured to said clamp member and to said support at its opposite end.

5. In a pad support of the class described, a relatively flat substantially rectangularly shaped 35 support member provided with a flange at each side thereof extending upwardly, vertically slotted hinge members extending at right angles to one of said flanges, a flap provided with offset 40 hinge members with pins mounted in said slots shiftable upwardly and downwardly therein, said flap member provided with a handle portion extending from one end at one side thereof, a spring actuated clamp member mounted at one end of 45 said support, including a pin mounted in the extended ends of said flange members, a clamp member pivotally mounted on said pins, a torsion spring mounted on said pins and secured to said clamp member and to said support at its opposite end, said support provided with a downwardly 50 extending lip at its backward end.

6. In a pad support of the class described, a relatively flat substantially rectangularly shaped support member provided with a flange at each side thereof extending upwardly, vertically slotted 55 hinge members extending at right angles to one of said flanges, a flap provided with offset hinge members with pins mounted in said slots shiftable upwardly and downwardly therein, said flap member provided with a handle portion 60 extending from one end at one side thereof, a spring actuated clamp member mounted at one end of said support, including a pin mounted in the extended ends of said flange members, a clamp member pivotally mounted on said pins, a torsion 65 spring mounted on said pins and secured to said clamp member and to said support at its opposite end, said support provided with a downwardly extending lip at its backward end, and a securing 70 member secured to a desk or table provided with a horizontal slot near its upper side adapted to receive said lip member on said support.

7. In a pad holder of the class described, a relatively flat pad supporting member provided 75

with hinge members at one side thereof, a flap member provided with offset extended hinge members shiftably connected with the hinge members on said support, and a spring clamp pivotally connected with the one end of said pad support provided with an upper extended portion adapted to engage the stub of the pad adjacent the perforate line therein.

8. In a pad holder of the class described, a relatively flat pad supporting member provided with hinge members at one side thereof, a flap member provided with offset extended hinge members shiftably connected with the hinge members on said support, a spring clamp pivotally connected with the one end of said pad support provided with an upper extended portion adapted to engage the stub of the pad adjacent the perforate line therein, said flap member being spaced at one end some distance from said spring clamp member.

9. In a pad holder of the class described, a relatively flat pad supporting member provided with hinge members at one side thereof, a flap member provided with offset extended hinge members shiftably connected with the hinge members on said support, a spring clamp pivotally

connected with the one end of said pad support provided with an upper extended portion adapted to engage the stub of the pad adjacent the perforate line therein, said flap member being spaced at one end some distance from said spring clamp member, said flap member provided with an extended handle portion extending outwardly past the back side of said pad.

10. In a pad holder of the class described, a relatively flat pad supporting member provided with hinge members at one side thereof, a flap member provided with offset extended hinge members shiftably connected with the hinge members on said support, a spring clamp pivotally connected with the one end of said pad support provided with an upper extended portion adapted to engage the stub of the pad adjacent the perforate line therein, said flap member being spaced at one end some distance from said spring clamp member, said flap member provided with an extended handle portion extending outwardly past the back side of said pad, and means for readily connecting and disconnecting said support with a table.
